UNITED STATES PATENT OFFICE.

MORRIS W. POOL, OF BROOKLYN, NEW YORK, ASSIGNOR TO REMINGTON TYPEWRITER COMPANY, OF ILION, NEW YORK, A CORPORATION OF NEW YORK.

TYPEWRITING MACHINE.

Application filed August 31, 1927. Serial No. 218,639.

My invention relates to type bar contact devices or anvils, and the object of the invention is to provide a new and improved anvil in which the noise due to the coaction of the type bars and the anvil will be minimized.

The gist of the invention lies in the provision of a series of openings or slots formed in the striking surface of the anvil which is tubular in cross section, the type bars being adapted to strike the anvil between the slots which interrupt and break up the sound waves resulting from the type bar blows.

To the above ends, the invention consists in the features of construction, combinations of devices and arrangements of parts hereinafter described and particularly pointed out in the claims. In the accompanying drawings which illustrate three different forms of the invention,

Fig. 1 is a fragmentary front elevation showing the type bar support or segment with one form of my invention applied thereto.

Fig. 2 is a vertical, sectional view taken centrally of the segment and showing a type bar in contact with the anvil, said Fig. 2 being drawn to a larger scale than Fig. 1.

Fig. 3 is a front elevation, drawn to an enlarged scale, of the type bar anvil shown in Fig. 1.

Fig. 4 is a transverse, sectional view taken on a plane indicated by the section line 4-4 in Fig. 3 and looking in the direction of the arrow at said line.

Fig. 5 is a view corresponding to Fig. 4 but showing a modification wherein the anvil is slotted at opposite faces.

Fig. 6 is a view corresponding to Fig. 3 but showing still another modification wherein the slots are disposed in parallelism instead of radially as in the Figs. 1-4 construction.

Fig. 7 is a sectional view taken on a plane indicated by the section line 7-7 in Fig. 6 and looking in the direction of the arrow at said line.

Referring first to the construction illustrated in Figs. 1 to 4, the type bar segment or support 1 is that of a No. 12 Remington typewriting machine to which my invention is shown as applied. Said segment 1 is secured by screws 2 to the framing 3 of the machine, below and somewhat forward of the platen 4. The segment 1 is formed with

a series of guide slots radiating from a common point somewhat below the printing point on the platen as is well understood, and adapted to these guide slots are type bars 6 each provided at its outer end with a type block 7 having an upper case type and a lower case type that selectively cooperate with the front face of the platen 4. The type bars 6 are pivoted on a common fulcrum wire 8 secured to the segment 1 and are actuated each by the usual train of key controlled devices, being swung thereby upward and rearward on the fulcrum wire 8 to printing position. As they approach the platen, the types cooperate with a guide opening 9 in a center guide 10 secured by screws 11 to the front of the segment.

My improved anvil or contact device, designated as a whole by the numeral 12, is, as illustrated, in the form of a metal tube which is bent to arcuate shape and is adapted to a seat provided by a depression or groove 13 formed in the front face of the segment 1. The groove 13 is of arcuate shape and the tubular anvil 12 conforms to this shape, so that it may readily be slid into and out of place in its seat or groove, it having both of its ends open for this purpose. The groove is open at the front, as indicated at 14, so that when the anvil is in place its striking face is exposed for cooperation with the type bars. As will be understood from Fig. 2, while the opening 14 permits the anvil 12 to protrude forward so that its striking face is presented to the printing type bars, the width of the opening is too narrow to permit forward displacement of the anvil. Endwise displacement of the anvil in its seat or groove is prevented by closures or plates 15 which are detachably secured to the top of the segment by screws 16. Removal of the plates permits the anvil to be readily slipped out and replaced when desired.

In carrying out my invention, I provide the striking face of the anvil 12 with a series of openings, which as shown in the Figs. 1-4 construction are in the form of radial slots or kerfs 17. These correspond substantially to the number of type bars 6 and are so disposed that the type bars are adapted to strike on the solid portions of the anvil between the slots, these solid portions being designated for descriptive purposes by the numeral 18. As will be plain from Fig. 3,

each type bar when in striking position will be in substantial parallelism with the slots at its opposite sides. These slots will interrupt and disintegrate the sound waves resulting from the contact of the type bar with the anvil, thereby minimizing the noise without sacrificing the advantages resulting from associating the type bar with an anvil or contact surface of tempered metal. As is well understood, to obtain the best results the anvil is so disposed that the type bar will engage with it just prior to contact with the platen, whereby the printing effect is obtained by a "whipping over" of the portion of the type bar above its point of arrest by the anvil. Uniformity of printing requires that the contact surface shall remain in its finely adjusted relationship with the printing face of the platen, and this, of course, can not be obtained with anvils having soft and easily worn striking faces. A hard-surfaced anvil, on the other hand, is ordinarily noisy, but by the use of my invention the noise is minimized. To eliminate noise as much as possible, the bore of the tube 12 may be filled with a core piece 19 of rawhide or other suitable material.

The principle of breaking up the sound waves by transverse slots may be applied in a number of ways to tubular anvils besides the manner disclosed in the Figs. 1-4 form. In Fig. 5, a modification is illustrated wherein the tube 20 is provided, as before, with slots 21 at its front or striking face and may also be provided with openings or slots 22 at its rear. The rear slots 22 may correspond in disposition and arrangement with the slots at the front or striking face, if preferred. The Fig. 5 construction has the further advantage of being readily reversible, whereby the life of the anvil may be prolonged.

Another modification is illustrated in Figs. 6 and 7. In this construction, the anvil 23 is provided with a series of parallel slots 24 in place of the radially disposed slots of the Figs. 1-4 construction. These parallel slots as illustrated are vertical when the anvil is in place in the machine. The type bars, particularly those near the ends of the set, strike crosswise of the slots but as will be plain from a consideration of Fig. 7 said type bars always contact with the solid portion of the anvil as at 25, this number indicating the striking points of the type bars.

My invention has proved to be effective in practice and it has the merits of being simple and cheap to manufacture, besides being adapted to replace other styles of anvils in existing makes of typewriting machines with-

out necessitating material alterations in said machines.

What I claim as new and desire to secure by Letters Patent, is:—

1. The combination of a platen, a plurality of type bars, and an arcuate tube arranged in the paths of the type bars so as to be struck at different points by said type bars as they near the ends of their printing strokes, the tube being formed with openings between the striking points of the type bars.

2. The combination of a platen, a plurality of type bars, and a metal anvil with which said type bars cooperate, said anvil being circular in cross section and formed with transverse kerfs.

3. The combination of a platen, a plurality of type bars, and a metal anvil with which said type bars cooperate, said anvil being circular in cross section and formed with transverse kerfs, the number of said kerfs corresponding substantially with the number of type bars.

4. The combination of a platen, a type bar support, type bars mounted thereon, and an anvil seated in a depression in said support and provided with a series of slots extending crosswise of the anvil.

5. The combination of a platen, a type bar support, type bars pivoted thereon, and an arcuate tube seated in a depression in said support and provided with a series of converging slots extending radially of the tube, the type bars being adapted to strike the tube between the slots.

6. The combination of a platen, a vertical type bar support, type bars pivoted thereon and adapted to coact with the front face of the platen, and an arcuate metal anvil secured to said support and provided at its striking face with a series of converging slots extending transversely of the anvil, the type bars being adapted to coact with the anvil between the slots.

7. The combination of a platen, a vertical type bar support, type bars pivoted thereon and adapted to coact with the front face of the platen, and an arcuate anvil secured to said support and provided at its striking face with a series of converging slots extending transversely of the anvil, the type bars being adapted to coact with the anvil between the slots, and the opposite face of the anvil being also provided with a plurality of openings or slots.

Signed at the borough of Manhattan, city of New York in the county of New York and State of New York, this 30th day of August, A. D. 1927.

MORRIS W. POOL.
